UNITED STATES PATENT OFFICE.

CHARLES DOERING, JR., OF OAK PARK, ILLINOIS.

LIQUID-DISPENSING APPARATUS.

1,241,353.

Specification of Letters Patent. Patented Sept. 25, 1917.

Application filed March 25, 1915. Serial No. 16,958.

To all whom it may concern:

Be it known that I, CHARLES DOERING, Jr., citizen of the United States, residing at Oak Park, in the county of Cook and 5 State of Illinois, have invented certain new and useful Improvements in Liquid-Dispensing Apparatus; and I do hereby declare the following to be a full, clear, and exact description of the invention, such as 10 will enable others skilled in the art to which it appertains to make and use the same.

This invention has for its object to provide an improved device for dispensing liquids and which is further adapted to be 15 filled with cold liquids and maintain the same in this condition for a relatively very long period.

The invention has for its particular object to provide an apparatus of this character which includes a receptacle for liquids 20 equipped with a hollow base rigid therewith and adapted to be removed with the receptacle from a suitable support and emptied at the time that said receptacle is being 25 re-filled.

Another object of this invention is to provide a receptacle of the character set forth which is portable and adapted to be filled with liquid at a source of supply of 30 such liquid at the desired temperature and may then be returned to the place where such liquid is to be dispensed for consumption.

A further object of this invention is to 35 provide a liquid dispensing device in which the receptacle for liquids is not accessible to the hands and which is adapted to be filled and emptied through a faucet disposed on the exterior thereof and which is 40 further guarded against the admission of dust and similar impurities adapted to affect the liquid contents thereof.

A further object of the invention is to 45 provide a liquid dispensing device in which the faucet is so disposed relatively to the drip pan as to obviate the use of tumblers or similar drinking cups, necessitating the use of the individual paper cups supplied from a cup dispensing device.

50 In the accompanying drawings, illustrating a suitable embodiment of the invention:

Figure 1 is a front elevation of a dispensing apparatus embodying my invention; a stand, or similar support for the 55 same, being shown in fragment.

Fig. 2 is a horizontal section of the device on the line 2—2 of Fig. 3.

Fig. 3 is a central, vertical, longitudinal section on the line 3—3 of Fig. 1.

Fig. 4 is a horizontal section on the line 4—4 of Fig. 1.

Referring now to said drawings: "A" indicates the housing of a liquid dispensing device embodying my invention, the same being preferably cylindrical and provided 65 with a dished upper wall and a flat lower wall, the latter preferably constituting the upper wall of a drip pan rigidly mounted upon said housing and constituting a part thereof. Mounted within said housing "A" 70 is an inverted bottle "C" of smaller diameter than the cylindrical wall of said housing "A" and of less length than said housing; said bottle being suitably supported concentrically, relatively to and between 75 the ends of said housing, by means of suitable frames and braces "D" and "E", some of the latter extending radially from the bottle to the circumferential wall of the housing and others being vertically dis- 80 posed between the ends of the bottle body and the end walls of said housing. The said frames and bases are preferably made of wire having relatively small cross section so as to provide as little heat conduct- 85 ing area therein as possible. The said bottle "C" is thus maintained rigidly in a fixed position relatively to the housing "A" and the free spaces between the same and said housing are filled with a suitable non-heat- 90 conducting material such, for example, as ground cork, saw-dust and the like.

The mouth of the bottle is closed by means of the stopper "F", which may consist of cork or other suitable material. A discharge pipe "G" extends to the inner end of said stopper "F" and connects at its other end with the faucet "H" disposed exteriorly of the housing and which is mounted upon a flanged plate "I" secured to the 100 exterior of the latter, there being a free space between said plate "I" and the circumferential wall of the housing. The said pipe "G" connects with the inner projecting end of the nipple "J" of the faucet by 105 means of a sleeve "K" of cork, or similar material, which is a poor conductor of heat and which spans the gap between the opposed ends of the nipple "J" and pipe "G".

A small pipe "L" through which air is 110

adapted to be admitted to and exhausted from said bottle as the water levels decrease and rise, extends from a point contiguous to the upper end of the interior of the 5 bottle through said stopper "F" and terminates in an opening in the circumferential wall of the housing which communicates with the free space between the plate "I" and said wall. An open space is left between the flange of said plate "I" and the 10 opposed wall of the housing at one side of the faucet through which air may be admitted to the said pipe "L" to be conducted thereby into said bottle, and air from the latter may be similarly exhausted therefrom.

Water or other liquid contained in the bottle "C" is drained from the latter through said faucet "H" and is also admitted through said faucet by attaching a 20 hose or a funnel thereto, when the housing is laid on its side, and maintaining said faucet open to admit such water. It will be seen that the said pipe "L" is bent within the 25 bottle "C" to extend along one side of the latter so that while water is being admitted, as above set forth, the air displaced by the admitted water may be exhausted from the bottle through said pipe.

The base "B" of said housing "A" is preferably made of cast iron or similar material and is of greater diameter than said housing. It is provided at the point beneath the faucet "H" with an opening "M" bordered by a rectangular lip "N", the drippings from said faucet being adapted to be received in said base "B" through said opening "M". The said lip "N" is so disposed relatively to the discharge spout of 30 said faucet "H" as to require a drinking cup to be filled to be held at a very sharp incline to the vertical axis of the housing or its own normal vertical axis and this angular disposition required prevents the 35 use of drinking glasses, tin cups, or similar drinking vessels but necessitates the use of individual paper drinking cups. These are supplied from a drinking cup dispensing device "O" removably secured to the 40 top wall of the housing "A". The latter is provided on its upper wall with a rectangular flange "P", which is adapted to be received within the hollow base "Q" of the dispensing device; the latter being provided 45 with a peripheral flange "R" adapted to be engaged by two latch members "S" adapted to be turned to engage the flange "R" or disengage the same for purposes of removing said dispensing device. Mounted upon 50 the said upper wall within the flange "P" is a bail "T", by means of which said housing may be conveniently carried from the point 55 of consumption of the liquid to the point at which the supply of such liquid is replenished and vice versa.

The opening "M" in the base "B" is sufficiently large to admit drinking cups to be inserted therein after the same have been used and has sufficient capacity to contain all the drip water which would normally be wasted. This hollow base is emptied at the point where the supply of liquid is renewed and may be cleansed at this point previous to replacement of the device at the point where said liquid contained in the 75 device is to be consumed.

I claim as my invention:

1. A liquid dispensing device comprising a housing, an inverted bottle mounted within the same concentric therewith and between the ends thereof, there being a space 80 completely surrounding said bottle and constituting insulation containing space for preventing changes in temperature of the bottle and its contents, a stopper for the mouth of the bottle, a faucet on the housing connection between said faucet and said bottle through said stopper, and an air tube having one end opening externally of said housing and projecting above the normal 85 water level within the bottle, the latter adapted to be filled with liquid and emptied through said faucet and a dished plate on said housing from which said faucet projects, said plate covering the mouth of said 90 air tube, there being an opening between said plate and said housing for the passage of air.

2. A liquid dispensing device comprising a receptacle for the liquid, a housing for the 100 same, a faucet on the exterior of said housing connected with the discharge end of said receptacle, an air inlet and outlet tube extending from a point above the normal water level in said receptacle to an opening in said 105 housing, said receptacle adapted to be filled with liquid and emptied through said faucet and a dished plate on said housing from which said faucet projects, said plate covering the mouth of said air tube, there being an opening between 110 said plate and said housing for the passage of air.

3. A liquid dispensing device comprising a portable housing adapted to receive and discharge liquid, a hollow base rigid with 115 said housing, a faucet on the latter, there being an opening in said hollow base below said faucet for receiving drippings therefrom, the walls of said opening disposed relatively adjacent to the delivery end of 120 the faucet to prevent placing a tumbler or the like under said faucet and whereby the lower side of a drinking vessel will be disposed nearly horizontally to receive liquid from said faucet.

4. A liquid dispensing device comprising a portable housing adapted to receive and discharge liquid, a hollow base rigid with 125 said housing, a faucet on the latter, there being an opening in said hollow base below

said faucet for receiving drippings therefrom, the walls of said opening terminating adjacent to said faucet to prevent the use of a tumbler whereby when a drinking vessel is placed to receive liquid from the faucet the lower side wall thereof will be positioned nearly horizontally, and means at the top of the housing for removably mounting a flexible drinking cup dispensing device vice.

5. A liquid dispensing apparatus, comprising a closed rigid, metallic housing or casing, a liquid-holding non-metallic receptacle of smaller dimensions than the 15 housing or casing interior and mounted therein so as to provide space entirely about said receptacle, a faucet secured to the housing or casing, a conduit intermediate of the faucet and the lower end of said receptacle 20 for conveying the liquid when the faucet is opened, the portion of said conduit adjacent the inner end of the faucet being non-metallic and yielding, and air-conducting means intermediate of the housing or casing exterior and the upper portion of said receptacle interior.

6. A liquid dispensing apparatus, comprising a closed housing or casing, a liquid-holding receptacle of smaller dimensions than the housing or casing interior, non-heat conducting matter intermediate said receptacle and the walls of the housing or casing, a faucet secured to the housing or casing, a conduit intermediate of the faucet and the lower end of said receptacle for conveying liquid, a portion of said conduit adjacent the inner end of the faucet being composed of non-heat conducting material, an air conduit extending into the upper part of the receptacle interior and communicating with the housing or casing exterior, and an escutcheon or cover plate secured about the orifice of said air conduit so as to provide an air chamber.

In testimony whereof I have signed my name in presence of two subscribing witnesses.

CHARLES DOERING, Jr.
